UNITED STATES PATENT OFFICE.

CHARLES ERNEST JONES, OF CHICAGO, ILLINOIS.

DESIGN FOR AN ARM-POCKET FOR OVAL BRACKET-BACKS.

51,385.

Specification for Design.

Patented Oct. 16, 1917.

Application filed August 18, 1917. Serial No. 187,025. Term of patent 3½ years.

To all whom it may concern:

Be it known that I, CHARLES ERNEST JONES, a citizen of the United States, residing at Chicago, in the county of Cook and State of Illinois, have invented a new, original, and ornamental Design for an Arm-Pocket for Oval Bracket-Backs, of which the following is a specification, reference being had to the accompanying drawing, wherein—

Figure 1 is a plan view,

Fig. 2 a side view,

Fig. 3 a front elevation, and

Fig. 4 an inverted plan view of an arm pocket for oval bracket backs, showing my new design.

I claim as my invention:

The ornamental design for an arm pocket for oval bracket backs, as shown.

CHARLES ERNEST JONES.
